UNITED STATES PATENT OFFICE.

HANS O. SWOBODA, OF EDGEWOOD, PENNSYLVANIA, ASSIGNOR TO EXCESS INDICATOR COMPANY, A CORPORATION OF PENNSYLVANIA.

EXCESS-INDICATOR.

1,144,335.

Specification of Letters Patent. Patented June 22, 1915.

Application filed May 27, 1913. Serial No. 770,223.

To all whom it may concern:

Be it known that I, HANS O. SWOBODA, a citizen of the United States, and a resident of Edgewood, in the county of Allegheny and State of Pennsylvania, have made a new and useful Invention in Excess-Indicators, of which the following is a specification.

This invention relates to excess current indicators, that is, those devices included in an electric circuit which are not actuated under normal conditions but which are only actuated upon passing more than the normal amount of current through the line.

Broadly stated, the present invention constitutes a simple and effective means for causing a "flickering" of the lights in a lamp circuit when an increase of current beyond the normal amount passes through the line, and if a further increase of current occurs, the "flickering" will cease and the lamps will become dimmed.

The figure in the drawing is a diagrammatical view of one form of the invention.

Referring now to the drawing by numerals of reference: 1 and 2 are the terminals of one leg of the line A and 3 and 4 are the terminals for the other leg of the line B. In the conductor A is a series coil 5 of a relay 6. The coil 5 is held on a bracket 7 which carries an armature 8 on which is a contact 9 adapted to contact with the contact 10 when the coil 5 attracts armature 8.

11 is a coil having a shunt winding 12 connected to the bracket 7 at 13 and to the conductor B at 14. The same coil 11 is provided with divided windings 15 and 16, in the present instance connected to opposite sides of the line. The winding 15 is connected to the conductor B at 17 and 18, and the winding 16 is connected to conductor A at 19 and 20.

Within the coil 11 is the core 21 which carries an insulated bar 22 supporting contacts 23 and 24 adapted to contact with the contacts 25 and 26.

When the parts are in the position shown, the current may enter at 1, passing through the conductor A, through the contact 23, up through the coil 5 and out through 2. The return circuit passing through B may come in at 3, pass through contacts 26 and 24 and out through 4. If an abnormal current passes through the line, however, the coil 5 will be energized so as to pull down armature 8 and close contact between 9 and 10;

the shunt winding 12 will then be energized through the bracket 7 and the conductor B. The shunt winding is really the winding for the solenoid core 21, and as soon as that part of the coil surrounded by the winding 12 is energized the coil 21 will have motion imparted to it to break contacts 23, 24, 25 and 26, and having broken the contacts, and inasmuch as the circuit is broken the coil 5 will be deenergized so that the armature 8 will move away from the coil under the action of the spring 27. As soon as contacts 9 and 10 are broken, the switch consisting of the solenoid 21 and the bar and its contacts will drop back into place and make contact between 23, 24, 25 and 26 so that the lights will come on again. There still being more than a normal amount of current, the armature 8 will be pulled down, the coil 12 energized, and the solenoid will have movement imparted to it to again break the current. This will happen with sufficient rapidity to cause a "flickering" of the lamps. As soon as the abnormal current demand ceases to exist, the apparatus will be restored to the position shown in the drawing. If the abnormal current happens to be above a determined value, instead of "flickering", the breaking of contacts 23 and 24, and 25 and 26 will cause the current to be shunted past the poles of the switch through the divided portions 15 and 16 of the coil 11, and while the "flickering" will cease, the lamps will be dimmed so that the consumer will know that an abnormal current demand is being made and so that he will rectify this unusual demand.

While I have specifically described one form of my invention, I do not wish to be limited to the details thereof, but reserve the right to make such changes and alterations as properly come within the scope of the claims without departing from the spirit thereof.

Having thus described my invention, what I claim is:

1. The combination of a main line electric circuit, a switch in the main line electric circuit, electro-responsive means associated therewith for intermittently opening and closing the switch upon a predetermined excess demand on the main line and electro-responsive means to hold the switch open during a greater excess load on the main line and for increasing the resistance in the main

line during the period the switch is held open, and permanent connections between the second mentioned means and the main line.

- 5 2. A main supply circuit, and a circuit supplied therefrom, electro-responsive means associated therewith for intermittently increasing and restoring the resistance between the main supply circuit and the circuit supplied therefrom, when the resistance of the supplied circuit falls to a certain predetermined value, and means permanently con-

nected to the supply line for maintaining the increased resistance when the resistance of the supplied circuit falls below a certain other predetermined value.

In testimony whereof, I have hereunto subscribed my name this first day of May, 1913.

HANS O. SWOBODA.
